UNITED STATES PATENT OFFICE.

JOHN KARITZKY, OF GARWOOD, NEW JERSEY, ASSIGNOR TO GARWOOD COMPANY, A CORPORATION OF NEW JERSEY.

TOGGLE.

1,374,925.

Specification of Letters Patent.

Patented Apr. 19, 1921.

Application filed April 2, 1919. Serial No. 287,042.

To all whom it may concern:

Be it known that I, JOHN KARITZKY, a citizen of the United States, and residing at Garwood, in the county of Union and State 5 of New Jersey, have invented certain new and useful Improvements in Toggles, of which the following is a specification, taken in connection with the accompanying drawing.

10 My invention relates to toggles and more particularly to a toggle in which the hinge member can be readily placed or changed by the mechanic. It further relates to such a toggle in which the hinge member is not 15 permanently secured to the toggle, as by riveting or other similar means.

My invention further relates to a toggle having preferably equal length of arms, the pivoting member being located substantially 20 equi-distant from the end of each arm. Also to such a toggle in which one of the arms will overbalance the other so that the parts will position themselves.

25 My invention further relates to such a toggle in which the head is formed preferably of spring material, which can be opened by the operator to insert the hinge member, or if a hinge member is already mounted in the head he can readily remove it in case he 30 desires to substitute another form of hinge member.

35 My invention further relates to such a spring headed toggle which is stamped out of sheet metal. At the same time that it is stamped, or subsequently, it may be provided with seats for the hinge member and also, though not necessarily, with one or 40 more stops. These stops are preferably formed by crimping over one or both of the free ends of the arms of the head so that they will engage with the bolt or other member and insure the proper alinement of the head with the bolt when it is inserted in the hole in the wall.

45 My invention further relates to a toggle which is stamped from sheet metal and in which some of the metal is crimped or bent within the body of the head to make one end of the head heavier than the other end, 50 and also to add strength to the complete toggle.

55 My invention further relates to certain details of construction and combinations which will be more fully described in the specification and pointed out in the claim,

and to a strong serviceable toggle which can be manufactured at minimum expense.

I have shown in the accompanying drawings different embodiments of my invention, but of course it is clearly understood that 60 my invention is not to be confined to the particular forms shown by way of example except as required by the scope of my claim.

In the accompanying drawings the same reference numerals refer to similar parts in 65 the several figures.

Figure 1 is a side elevation of one form of my improved toggle, in which the hinge member is an ordinary square nut;

Fig. 2 is an end elevation of Fig. 1;

Fig. 3 is a plan view of my improved toggle provided with stops, and with a hinge member in the form of a diamond shaped nut;

Fig. 4 is a vertical section substantially 75 on the line 4-4 of Fig. 3 looking in the direction of the arrows, the hinge member and bolt being shown in side elevation;

Fig. 5 is a plan view of a blank from which my toggle bolt is preferably stamped;

Fig. 6 is a side elevation of my toggle bolt provided with a true trunnion nut;

Fig. 7 is a detail plan view of the hinge member shown in Fig. 6;

Fig. 8 is a vertical section through a wall, 85 and through the work to be supported, showing an old form of toggle bolt;

Fig. 9 is a vertical section through a wall and showing my improved toggle in operation;

Fig. 10 is a side elevation of one form of my toggle in which the hinge member is an ordinary T headed bolt; and

Fig. 11 is a detail plan view of the T headed bolt shown in Fig. 10.

In the illustrative embodiment of my invention 1 is a head of a toggle bolt having ends 2 and 3 of substantially the same length, with a hinge member 4 mounted substantially equi-distant between the ends 5 100 and 6. This toggle head may be made in various ways provided the ends 2 and 3 are of practically the same length and the pivoting member or hinge member is mounted so that the strain upon the end 2 will balance the strain or tension upon the end 3 when the toggle head is mounted in the wall as shown for example in Fig. 9. To insure that one end of the toggle head will overbalance the other, so that the heavier end 110

will drop into its proper operative position, as shown in Figs. 1, 2, 3 and 9, I may in any suitable manner increase the weight of one of the ends as, for example, the end 5 number 2. This of course may be done in various ways.

For ease, economy and speed in manufacture, I form my toggle head from stamped sheet metal. I take a blank such 10 as 7, Fig. 5 and bend it at 8 to form the interior reverse U shaped member 9 and then again bend the blank at 10—10 to form the side 11—11 of the head shown in Figs. 2 and 3. At the time the blank is stamped, 15 or subsequently, I preferably provide it with hinge seats to coöperate with the hinge member, whatever that form of hinge member may be. One form of hinge seat, and the one that I preferably use, is 12—12 formed by stamping out a portion of the blank. 20

When the blank is bent as shown in Figs. 2 and 3, the end 2 will overbalance the end 3 even though the two ends are of the same length. This is due to the fact that additional or surplus metal is formed into the head of the toggle on the end 2 and not on the end 3. This additional bend or crimp of the metal forming the U shaped member 9 also strengthens the entire toggle head while 25 not interfering with the operator moving out the arms 13—13 to insert, or change, the pivoting or hinge member.

This hinge member may be the square nut shown in Figs. 1 and 2; or the diamond shaped nut 14, Fig. 3, in which the ends 35 15—15 of the nut are, in effect, trunnions; or the hinge member may be a true trunnion nut 16, Fig. 7, having trunnions 17—17; or the hinge member may be a T headed bolt 40 18, Figs. 10 and 11 in which the T head 19 would be made to coöperate with the seats 12—12, or any other suitable form of hinge member may be used. The hinge member, in Figs. 10 and 11 is put under 45 tension by the nut 20 coöperating with the screw thread 21.

I preferably, though not necessarily, provide one or more stops on the arms 13 so that they will engage with the bolt 22 to keep the 50 toggle head 1 in alinement with the bolt while it is being inserted in the hole 23, Fig. 9. These stops 24 are preferably formed by bending over one or both of the free ends of the arms 13—13.

55 It is often desirable to use toggle bolts in walls or partitions or similar locations 25, Fig. 9, in which the free or air space 26 is limited. It is found that it is often not feasible to use an ordinary toggle bolt, having ends of unequal length to insure that the bolt will drop into its operative position as shown for example in Fig. 8, for the reason that the air space 26 is too narrow or limited. By my invention, in which the

two ends of the toggle head are of equal 65 length, it can be mounted in a wall where the air space 26 is of minimum width.

In these walls or partitions, which are quite frequently made of hollow tile, the 70 drill will start to drill the hole 23, Figs. 8 and 9, of the correct diameter until it has penetrated a certain distance from the face 27 of the wall. Further drilling will cause the hollow tile, or other material of which the wall is made, to break away and fall on the interior of the wall leaving an irregular funnel shaped opening 28. The contour 75 of this opening will vary with the material of the wall and the resistance met.

In Fig. 8 I have shown an old form of 80 toggle bolt having a riveted nut 35 and a head 29 in which the end 30 is of greater length than the end 31, this being the common expedient in the trade to overbalance one of the ends to insure that the toggle 85 head will assume a vertical position in the wall as shown in Fig. 8. It has been found in practice that a toggle head having ends of unequal length, as for example 30 and 31, will often assume, in time, and under 90 severe service conditions a position like that shown in dotted lines in Fig. 8, particularly if the work 32, to be held is subjected to vibration. This will permit the work to get loose and rattle. If the vibrations upon the work 32 are excessive, in this form of toggle head having unequal ends, the toggle head tends to work down into parallel relation with the bolt 33 and, in time, will work out 95 of the hole 23, permitting the work 32 to 100 drop with consequent damage and danger.

By my invention the toggle head 1 having ends 2 and 3 of equal length will straddle the opening 28 and the strains and stresses on the ends 2 and 3 will balance so that there will be no tendency for it to assume a position similar to that shown in Fig. 8, or to work parallel with the bolt 22 to permit the work rattling or falling.

Having thus described this invention in connection with illustrative embodiments hereof to the details of which I do not desire to be limited, except as required by the scope of the appended claim, what is claimed as new and what is desired to secure 115 by Letters Patent is set forth in the appended claim.

What I claim is:—

An article of manufacture comprising a 120 head of a toggle bolt stamped from spring sheet metal and provided at one end with a reversed bent or crimped portion to make that end heavier and stronger than the other end.

JOHN KARITZKY.
